UNITED STATES PATENT OFFICE.

WILLIAM A. BOYD, OF SYRACUSE, NEW YORK, ASSIGNOR TO FIRST NATIONAL BANK,
OF SYRACUSE, NEW YORK, A CORPORATION OF NEW YORK.

DESK.

1,232,649.

Specification of Letters Patent. Patented July 10, 1917.

Application filed July 19, 1915. Serial No. 40,675.

To all whom it may concern:

Be it known that I, WILLIAM A. BOYD, a citizen of the United States of America, and resident of Syracuse, in the county of Onondaga, in the State of New York, have invented new and useful Improvements in Desks, of which the following, taken in connection with the accompanying drawings, is a full, clear, and exact description.

10 This invention relates to certain improvements in desks or tables, and although applicable for general use is particularly adapted for use in banks, public reading rooms, offices and like places.

15 The primary object of the invention is to produce a desk which shall comprise substantially as a unitary article of manufacture all the accessories for writing and for the reception of writing materials and embodying a removable receptacle for receiving and retaining waste papers, so formed, arranged and positioned as not to interfere in any way with the use of the desk for writing purposes, and at the same time improving 20 the appearance as well as increasing the efficiency of the structure.

A further object is to provide a member inclosed by the structure and readily removable therefrom, adapted to removably 30 receive and retain separate letters and figures indicating the date.

Other objects relate to the specific construction and arrangement of the parts constituting the structure, as will more clearly 35 appear from the following description taken in connection with the accompanying drawings in which:

Figure 1 is a perspective view of the desk.

Fig. 2 is a vertical cross section of the 40 central portion of the desk showing the superstructure and waste basket comprising the invention.

Fig. 3 is a horizontal cross section on line 3—3, Fig. 2.

45 The desk as here illustrated comprises a suitable supporting structure or base —1— the exterior of which in this instance is faced with marble slabs, and is provided with a suitable flat top —2— likewise preferably formed of a plain slab of marble. In 50 the specific illustration the desk is substantially square and the central portion of each

side of the slab —2— is provided with a recess —3— each recess adapted to receive a removable tray —4— having a series of partitions —5— forming compartments adapted to receive checks, notes or other writing material. Preferably the marble slab —2— is covered by a plate —6— of transparent material such as glass, and as shown, of slightly less area than the slab —2— and adapted to cover the recesses —3— and form a closed upper side for the compartments of the tray —4— formed by the partitions —5—. The central portion of the slab —2— is provided with an opening —7— and the central portion of the glass plate then is likewise provided with an opening —8— of slightly greater area than and registering with the opening —7— forming a stepped portion or shoulder —9— adapted to form a bearing or support for the edge flange —10— of a waste basket supporting member —11— tubular in shape and closed at its lower end, and preferably for the purpose herein described, formed of thin sheet metal or other similar material.

A suitable tubular member —12— preferably formed of metal or other similar material, rests upon the upper surface of the glass plate —6— and is provided with a series of horizontal openings —13— for the reception of ink wells —15— adapted to be seated in openings —16— in the plate —6— and preferably the edge of the member —12— bordering the opening —13— is provided with a depending circumferential flange —17— adapted to fit into a stepped portion —18— formed in the plate —6— to hold the member —12— in desired position, and registering the opening —13— with the opening —16—. The sidewalls of the member —12— in this instance, 4 in number, are each provided with a curved recess portion —19— allowing easy accesses to the wells —15— and each sidewall has a suitable tray —19— for the reception of pens, pencils and the like, secured thereto preferably above the recess —19— by screws or bolts —20— or other suitable means.

100 The member —12— is provided with a horizontally disposed portion —21— and a vertically disposed portion —22— arising from the inner edge of the portion —21—

and a flange —23— arising from the outer edge of the portion —21— forming a channel for the reception of removable blocks —24— adapted to carry in any suitable manner letters and figures to indicate the date, and in the particular structure shown, the blocks are provided with a fabric covering —25— to which the letters may be secured. A suitable waste basket —26— of slightly less diameter than the member —11— and the portion —22— rests within and upon the member —11— and within the portion —22—. The structure so far described is covered and inclosed by a cap —27— having a depending marginal flange —28— resting within the flange —23— and upon the portion —21— and provided upon each side with a window comprising a suitable sheet —29— of transparent material such as glass secured in openings —30— in the side-walls of the cap and adapted to disclose the letters, and figures as positioned upon the member —24—. The cap likewise comprises an inner depending tubular portion —31— of less diameter at its lower end than the diameter of the basket —26— and extending below the upper edge of said waste basket to discharge waste, such as paper, into the same.

30 By removing the cap —27— the waste basket —26— is rendered readily accessible for removal and the members —24— may likewise be readily removed, or the letters and figures may be changed while the members remain in place. The ink wells are always in position for use at each side of the table and are supported in such manner that they cannot be tipped over, and the superstructure as a whole, and the waste basket constitute a most convenient and efficient accessory of the desk or table as a unitary article of manufacture.

Although I have shown and described one particular construction, form and arrangement of the parts, I do not desire to limit myself to any specific construction, form or arrangement, as many changes may be made in the details of the same without departing from the spirit of this invention as set forth in the appended claims.

What I claim is:

1. The combination with a desk of a super-structure arising therefrom comprising a tubular member having vertically disposed portions of different widths connected by a horizontally disposed portion, said horizontally disposed portion provided with a marginal flange, and a cap having diverging tubular walls, one of said walls engaged with said marginal flange and the other of said walls depending within the portion of less width of said tubular member, and an indicia carrying member resting on the horizontal portion of said tubular member, said cap provided with transparent portions dis-

closing the portion of said member adapted to carry indicia.

2. The combination with a desk of a super-structure arising therefrom comprising a tubular member having vertically disposed portions of different widths connected by a horizontally disposed portion, said horizontally disposed portion provided with a marginal flange, and a cap having diverging tubular walls, one of said walls engaged with 70 said marginal flange and the other of said walls depending within the portion of less width of said tubular member.

3. The combination of a desk having a recess and a waste receptacle in said recess, 80 of a super-structure arising from the desk about the recess and comprising a tubular member having vertically disposed portions of different widths connected by a horizontally disposed portion, said horizontally disposed portion provided with a marginal flange, and a cap having diverging tubular walls, one of said walls engaged with 85 said marginal flange and the other of said walls depending within the portion of less width 90 of said tubular member and adapted to direct waste into said waste receptacle.

4. The combination of a desk having a recess and a waste receptacle in said recess, 95 of a super-structure arising from the desk about the recess and comprising a tubular member, and a cap having a portion removably engaged with said tubular member and another portion depending within the tubular portion and adapted to direct waste into 100 said receptacle.

5. The combination with a desk having a plane top with a substantially centrally formed recess and a waste receiver located in said recess, of a tubular super-structure 105 rising from the table about said recess and having a tubular flange depending from its upper edge within the super-structure and adapted to direct waste into said receiver.

6. The combination with a desk having a plane top with a substantially centrally formed recess and a waste receiver located in said recess, of a tubular upwardly tapered super-structure rising from the table about said recess and open at its top and having 110 a tubular flange depending from its upper edge arranged within the super-structure and within the upper end of said waste receiver.

7. The combination with a desk of a super-structure arising therefrom, comprising a tubular member having vertically disposed portions of different widths connected by a substantially horizontally disposed portion, 120 a tubular cap removably engaged with the tubular member and an indicia-carrying member resting on the horizontal portion of said tubular member, said cap provided with a transparent portion disclosing a portion of 125 said member adapted to carry indicia.

8. The combination with a desk having a substantially plane top, of a super-structure having portions resting flat upon the upper surface of said desk, said portions provided with openings, recesses in said plane top registering with the openings in the super-structure, and flanges about the edges of said openings in the super-structure, and

additional recesses in said top portion for receiving said flanges. 10

In witness whereof I have hereunto set my hand this 14th day of July, 1915.

WILLIAM A. BOYD.
